UNITED STATES PATENT OFFICE.

ARCHIBALD C. MUIR, OF BRILLIANT, NEW MEXICO.

RAILWAY-TRACK EQUIPMENT.

1,345,389.

Specification of Letters Patent.

Patented July 6, 1920.

Application filed November 2, 1918. Serial No. 260,887.

To all whom it may concern:

Be it known that I, ARCHIBALD C. MUIR, a subject of the King of Great Britain, residing at Brilliant, in the county of Colfax 5 and State of New Mexico, have invented certain new and useful Improvements in Railway-Track Equipments; and I do hereby declare the following to be a full, clear, and exact description of the invention, such 10 as will enable others skilled in the art to which it appertains to make and use the same.

My invention relates to improvements in railway track equipment, and more particularly to a combined nut lock plate, rail brace and chair.

An important object of this invention is to provide a nut lock plate adapted for ready attachment to the ties and a rail, 20 whereby the same will engage the nuts securing the fish plate to the web of the rail and retain the same against accidental displacement.

A further object of the invention is to 25 provide means in connection with my improved nut lock plates, whereby the rails may be effectively prevented from spreading.

A further object of the invention is to 30 provide a device of the character described, which is of highly simplified construction, reliable in use and simple to apply to the standard rails.

A further object of the invention is to 35 provide a device of the character described, which, by virtue of its extreme simplicity and reliability in use, will meet with commercial success in a highly crowded art.

Other objects and advantages of the invention will be apparent during the course 40 of the following description.

In the accompanying drawings, forming a part of this specification, and in which like numerals are employed to designate like parts throughout the same,

45 Figure 1 is a perspective of a portion of a railway track, illustrating the application of one form of my invention,

Fig. 2 is a perspective of a nut lock plate embodied in the invention,

50 Fig. 3 is a perspective of a modified form of the nut lock plate,

Fig. 4 is a plan view of the nut lock plate and the anti-rail-spreading plate connected by a retaining bar, and

55 Fig. 5 is a perspective of a rail-engaging

plate adapted to co-act with the nut lock plate in preventing the rails from spreading.

In the drawings, wherein for the purpose of illustration is shown the preferred embodiment of my invention, the numeral 10 60 generically designates a nut lock plate adapted to traverse two ties. The nut lock plate is adapted to be arranged at a point to extend over the end portions of a pair of adjoining rails and thus be in position to 65 engage the nuts. My improved nut lock plate may be of any desired metal possessed of sufficient rigidity to withstand the strain incident to the passing of trains over the rails.

As clearly shown in Fig. 2, the nut lock plate comprises a flat base 11, having recessed portions 12 along its outer edge for the reception of railway spikes 13, which extend into the ties. The central portion 75 of the base plate 11 is provided with a recessed portion for the reception of the base of the rail. The outer portion of the base plate 11 is provided with a longitudinally extending overhanging shoulder 14 adapted 80 to extend over and contact with the outer side of the base of a rail. Formed integrally with the overhanging shoulder 14 and extending upwardly therefrom is a bracing strip 15, adapted to contact with the outer 85 side of the web of a rail. The lower portion of the brace 15 and the adjacent portion of the overhanging shoulder 14 are provided with rectangular openings 16 adapted to extend over the nuts of a rail joint. The 90 opposite side of the base plate 11 is provided with openings 17 adapted for the reception of spikes serving to retain the rails in position. As clearly shown in Fig. 1, the nut lock plate 10, shown in Fig. 2, is adapted 95 to traverse two ties and serve as a connecting means for the end portions of the adjoining rails.

In Fig. 3 there is shown a modified form of the nut lock plate, wherein the base 17 100 is adapted to rest upon a single tie and be secured thereto. In this form of the invention, the central portion of the plate 18 is recessed for the reception of the base of the rails 19. The outer portion of the plate 18 is provided with an overhanging shoulder 20, adapted to engage the upper portion of the outer side of the base of the rails 19. 105 As clearly shown in Fig. 3, the end portions of the shoulder 20 extend beyond the ends 110

of the base 18. A brace 21 is formed integral with the shoulder 20 and is provided with rectangular openings 22 adapted to extend over the nuts of the bolts extending through the web of the rail. The outer portion of the base 18 is provided with recesses 23 for the reception of spikes extending into the tie.

Adapted to be arranged on the opposite ends of the ties, I have provided a combined rail brace and anti-rail-spreading device generically designated by the numeral 24. As clearly shown in Fig. 5, the device comprises a base plate 25 adapted to be arranged beneath the base of a rail opposite either the nut lock plate 10 or 18. The member 25 has its central portion provided with a longitudinally extending recess for the reception of the base of a rail. The outer portion of the base 25 is provided with a shoulder 26, extending over the outer side of the base of a rail. Formed integrally with the shoulder 26, and extending upwardly therefrom, is a plain brace member 27, adapted to engage the rail and retain the same in a rigid position. Adapted to be arranged between the member 24 and either of the nut lock plates is a bar 28 secured to the ties by spikes or bolts 29 and 29', the spikes 29' passing through the inner ends of the plates 25 and 10 or 18 to hold the plates in engagement with the bar 28. As clearly shown, the end portions of the bar 28 extend into recessed portions 31 along the inner edges of the member 24 and either of the nut lock plates.

It will be apparent that the connection between the oppositely disposed plates will effectively prevent the rails from spreading.

While I have shown and described the preferred embodiment of my invention, it is understood that I may make such minor changes in arrangement and construction of parts, as will remain within the spirit of the invention and the scope of the appended claim.

Having thus described my invention, what I claim is:

A device of the character described comprising rail engaging members each having a base plate for fitting beneath the base of a rail and cut out longitudinally to provide a rail receiving seat, an overhanging shoulder formed integrally with the outer portion of the base plate for engaging the upper face of the base of a rail and having an upstanding extension for engaging the web of a rail and provided with nut receiving openings, a bracing bar extending between the rail engaging elements and fitting beneath the inner ends thereof, and securing elements extending through the inner end portions of the rail engaging elements and through the end portions of the bracing bar.

In testimony whereof I affix my signature in presence of two witnesses.

ARCHIBALD C. MUIR.

Witnesses:

T. C. SMITH,
C. E. ROUNDSLEY.
